UNITED STATES PATENT OFFICE.

DAVID W. BLACK, OF BUTLER, PENNSYLVANIA.

DEEP-WELL PACKER.

1,035,850.

Specification of Letters Patent. Patented Aug. 20, 1912.

Application filed April 12, 1909, Serial No. 489,365.

To all whom it may concern:

Be it known that I, DAVID W. BLACK, of Butler, Butler county, Pennsylvania, have invented a new and useful Deep-Well Packer, of which the following is a full, clear, and exact description, reference being had to the accompanying drawings, forming part of this specification, in which—

Figure 1 is a side elevation showing one form of my improved packer in unpacked position in the well; Fig. 2 is a similar view showing the packed position; Fig. 3 is a view similar to Fig. 2, showing an anchor packer; Fig. 4 is an enlarged sectional side elevation showing the details of the form of Figs. 1, 2 and 3; Fig. 5 is a partial section showing the preferred form of attachment after the tubing has been removed; Fig. 6 is a view similar to Fig. 1, showing my invention without the use of the locking dog or clutch; Fig. 7 is a view similar to Fig. 1, showing the invention applied to a disk packer; Fig. 8 is a sectional view corresponding to Fig. 5, showing the attachment of my device where oil and gas tubing are both used; and Fig. 9 is a sectional view of my packing device seated on a cut section of casing. Figs. 10 and 11 are detail views illustrating a construction in which the packer may be lowered by a cable.

My invention relates to the class of packers for deep wells, and its object is to provide a packer which will allow the tubing to be withdrawn while leaving the packer in place.

Heretofore, where packers have been attached to and lowered by the tubing, the packer must be removed whenever the tubing was withdrawn. The removal of the packer is not only difficult and costly; but this also entails the further labor of replacing the packer at or nearly the same location when the tubing is again lowered.

My invention overcomes this difficulty, and it consists in a packer, attached to and lowered by the tubing, but from which the tubing may be detached and withdrawn while leaving the packer in the well.

The invention further consists in providing a packer so arranged that the tubing may extend through it and thus pack the well at any desired point, while allowing withdrawal of the tubing.

In the drawings, I have shown my improvement as applied to a packer of the "Masseth" type, but it will be understood

that my improvement may be applied to any type of packer which is attached to and lowered by the tubing or line, whether it is a wall packer or a bottom or anchor 60 packer; and irrespective of the means for carrying out the packing operation.

In the drawings, referring particularly to the form of Figs. 1, 2, 4 and 5, 2 represents the tubular frame of the packer, and 3 the 65 expansible packer tube, made preferably of rubber, which fits around the tubular frame and bears at its upper end against a shoulder at the lower end of a coupling sleeve 4, screwed or otherwise secured to the upper 70 portion of the frame 2. At its lower end, the expansible rubber sleeve fits against the upper end of a hollow sleeve extension 5, screwed or otherwise secured to the sliding cone 6. The cone 6 fits telescopically around 75 the hollow packer frame 2, and is movable longitudinally thereof. 7 is a collar or band which surrounds the frame below the cone and is provided with upwardly projecting spring arms 8, having leaf springs 9, secured thereto. The springs 9 normally bear 80 against the sides of the hole, while the upper spade-like ends 10 of the spring arms are arranged to slide over the cone and be jammed against the wall of the well to afford a resistance against which the packer 85 can be expanded. The arms 8 are locked or held from action by any usual or suitable means which can be engaged and released by a rotary movement of the frame. In 90 using this type of packer, it is usually made right-handed, and is screwed on to a joint or stand of pipe or casing with the ring 7 locked. The packer is then lowered in the well, either at the end of the casing or between successive sections of the casing, and when at the desired point the pipe or casing is turned to the left and then lowered. Turning the casing to the left unlocks the 95 sleeve or collar 7 and the lowering then causes the slips 10 to be jammed between the cone and the sides of the well. This affords a resistance, and the weight of the casing resting on the rubber expands it to pack the well. In resetting at a lower point, 100 the pipe or casing is raised, then turned to the right, and then lowered and packed as before. If it is to be reset at a higher point, it is not necessary to turn the pipe or casing, as it may be pulled up and then lowered in the new position.

The above description applies to the well-

known "Masseth" type of packer; and I will now describe my improvement as applied to such packer. As above stated, these packers have been used by screwing the pipe or casing to their upper ends or to their upper and lower ends. Instead of this connection, I provide a hollow plug 11 of two different diameters between successive sections 12, 12 of the tubing. This plug in its larger external diameter is provided with a left-handed thread, which engages a corresponding internal thread in the upper portion of the sleeve 4 of the packer. The packer is hollow throughout, thus allowing the tubing to extend down through it, the plug 11 forming the only connection between the tubing and the packer. When this packer has been packed in the well, and it is desired to remove the tubing, all that is necessary is to turn the tubing in a right-handed direction, thus unscrewing the plug 11 from the packer when the entire tube may be lifted out of the well. This unscrewing has no effect upon the joints of the tubing, nor upon unlocking the packer, since both the packer and the joints are right-handed. When it is desired to replace the tube, the same plug 11 may be used, and when this plug reaches the upper end of the packer the tubing may then be turned in a left-hand direction to reengage the plug with the packer. In order, however, to avoid the necessity for thus re-screwing the tubing to the packer, I preferably interpose between the lengths of the tubing a short section 13, as shown in Fig. 5, having a circular disk or seat 14, under which is placed a surrounding gasket 15. This gasket is preferably slightly conical, and when the tubing is lowered to a point where the gasket reaches the top of the packer, the weight of the tubing will force the gasket down on and into the upper end of the packer, thus sealing this joint. In this case, the tubing will extend through the packer as before.

In order to prevent any accidental unpacking during the taking out or putting in of the tubing, at any time when it is disconnected from the packer, on account of the removal of the weight therefrom, I preferably provide a clutch device, which will lock the rubber in expanded position and prevent relative movement of the abutment 5 and the packer tube or frame 2. In the form shown, this clutch device consists of a sectionalized ring 16, as shown in Fig. 4, this ring being divided into a plurality of pieces, and having a conical portion 17, which is adapted to fit against a corresponding conical face on the inner portion of the extension 5. Between the lower end of this sectionalized ring 16 and the upper end of the cone 6, is placed a spiral spring 18, which normally forces the cone ring upwardly and inwardly. The sectionalized

ring is provided with inner ratchet teeth, and the barrel or frame 2 is provided with corresponding outer ratchet teeth for a suitable portion of its length, these two elements acting as a clutch. When the sleeves are jammed in the well, and the weight of the casing or tubing causes the frame to slide down through the cone, the spring clutch ring will slide up over the teeth on the frame, these teeth preventing any relative backward movement of the cone and the frame. When the packer is in packing position, therefore, the spring ring will lock the cone in the position where the rubber is expanded, thus preventing accidental unpacking.

In Fig. 3 the slips, cone, slip ring, &c., are done away with, this showing an anchor or bottom packer. In this case, the lower section 19 is arranged to slide over the tubular frame of the packer, so that when this section 19 reaches the shoulder 20 in the well or bottom of the well, the weight of the tubing or casing will then expand the rubber by the packer frame sliding down through the sleeve 19, which forms the resistance for expansion. In this case again, the clutch device may be employed for locking the section 19 in the position where the rubber is held expanded.

In Fig. 6, I show the same form of invention as in Fig. 1, except that instead of using the clutch to hold the packer in packed position, I secure to the upper end of the packer a length of casing 21. This casing is provided at its upper end with a coupling sleeve 22, corresponding to the sleeve 4 of Figs. 1 and 4, this having the left hand connection with the hollow plug 23, corresponding to the plug 11 of Fig. 4. In this case, the weight of the length or lengths of casing 21 will hold the packer in packed position when the tubing is removed. This is of advantage where it may be desired to change the position of the packer, because it will be difficult to change its position where the locking clutch device is employed.

In Fig. 7, I show my invention as applied to a spring disk packer in which 24 is the usual coil spring, 25 the slip ring, and 26 the slips. The tubular frame 27 is slotted in a vertical direction only to receive a pin 28, on the slip ring in order to prevent turning. The disk is, of course, not shown as it is supposed to have been broken before the spring has thrown the slips up over the cone, as shown in this drawing. In this form also, instead of the fitting 14, shown in Fig. 5, I provide in the length of oil tubing 29 a large fitting 30, having its lower end shaped to receive the rubber gasket 31, which corresponds to gasket 15 of Fig. 5. This gasket fits down on the top of a coupling 32, secured to the upper end of a casing section or sections 33, which are screwed

to the upper end of the packer, as shown in detail in Fig. 8. The fitting 30 has two openings through it, the oil tubing 29 being secured in one opening, while the gas tubing 34 extends through the other hole, both sets of tubing extending through closely fitting holes in the rubber gasket to prevent leakage. This form is of special advantage where it is desired to save the gas and at the same time obtain the oil. It will, of course, be understood that the fitting 30 is put in place after the tubing has been removed and after the well has been packed with the device of Fig. 4 or 6, or with any other form of packer.

The packing device such as shown in either Fig. 5 or Figs. 7 and 8 may be used to advantage in packing casing which has been corroded or eaten through. It often happens that where casing has been standing in a well for some time it becomes eaten through. In such cases heretofore the casing has been cut below the eaten-away portion and a packer has been lowered and packed below the water level; or a smaller packer with tubing attached has been packed inside of the remaining section of the tubing below the water level. In the latter case, the casing need not be cut. With the use of my improved packing device, such a well may easily be packed off to prevent the water entering the well by simply cutting off the casing below the leaking portion and then lowering a line of tubing with the packing device of either Fig. 5 or Figs. 7 and 8 upon the cut end of the casing. This does away with the necessity for a wall or anchor packer and allows the removal of the casing from the cut section upwardly.

Instead of lowering my packer upon a line of tubing, it may be lowered to place by a flexible cable. In this case, the flexible cable would be provided with a detachable connection with the top of the packer so that when the packer was lowered to the proper position the flexible cable could be released and drawn out. If the packer is an anchor packer, the casing can be lowered upon it and will pack it. Wall packers may be used in this case with the flexible cable, which will pack without rotation. In other words, I do not wish to limit myself to the use of tubing or lowering my packer to position, as it may be lowered by a flexible cable. One form of device for this purpose is illustrated in Figs. 10 and 11. In these figures, the numeral 35 designates the lower or letting-in tool at the lower end of the usual string of tools. This tool is provided with the squared shank 36, which engages a transverse member 37, having its ends engaged with an interior thread 38, at the upper end of the packer. The packer is lowered into the well by the cable to which the string of tools is attached, and after it

has been set in the usual manner, a quick jarring movement of the cable will break the arms of the transverse member 37 and thus detach the letting-in tool from the packer.

The advantages of my invention will be apparent to those skilled in the art. A simple and efficient means is provided by which the packer may be easily and quickly detached from the tubing to allow the tubing to be raised without moving the packer. At the same time, the packer is lowered into the well by means of the tubing itself. The rubber and expense incident to removing and replacing the packer are done away with, as well as the difficulty of repacking at the same point. The clutch device is also of advantage in avoiding accidental unpacking when the weight is taken off the packer.

My improvement may be applied to any type of deep well packer, whether a well packer either of the Masseth type or the disk packer, wherein a spring acts to force the slips on the cone after the disk is broken or bent; or an anchor packer or bottom packer. I do not intend to limit myself to the application of my improvement to any specific type of packer, having illustrated the Masseth packer merely to show the action of my device on one form of packer.

I consider myself to be the first to provide a packer which is lowered by the tubing or casing or line, and can then be detached therefrom so as to remove the tubing or casing without moving the packer.

I claim:

1. The combination with a well packer and a tubing arranged to extend continuously down through the packer, of a connector carried by an intermediate portion of the tubing and having a detachable engagement with the packer, whereby the tubing may be disconnected from the packer and withdrawn upwardly therethrough, the connection between the connector and the packer consisting of a screw-threaded engagement, the threads of which are of opposite hand to the threads of the tubing sections, substantially as described.

2. The combination with a well packer, of a connector having means for the attachment of well tubing thereto, and having a screw-threaded connection with the packer, of opposite hand from the threads of the tubing joints or connectors, the tubing passing continuously and freely down through the packer, and the said connector forming the only connection between the packer and tubing, substantially as described.

3. The combination with a well packer and a tubing arranged to extend continuously down through the packer, of a connector carried by an intermediate portion of the tubing and having a detachable engage-

- ment with the packer, whereby the tubing may be disconnected from the packer and withdrawn upwardly therethrough, the connection between the connector and the packer 5 consisting of a screw-threaded engagement, the threads of which are of opposite hand to the threads of the tubing sections, together with means for locking the packer in its packing position; substantially as described.
- 10 4. The combination with a well packer and a tubing arranged to extend continuously down through the packer, of a connector carried by an intermediate portion of the tubing and having a detachable engagement with the packer, whereby the tubing may be disconnected from the packer and withdrawn upwardly therethrough, the connection between the connector and the packer 15 consisting of a screw-threaded engagement, the threads of which are of opposite hand to the threads of the tubing sections, together with means carried by the tubing for closing the upper end of the packer when the connector has been removed.
- 20 5. A deep well packer having a connecting device for tubing arranged to permit the

tubing and device to be disconnected from the packer and withdrawn after the packer operation, and a second device arranged to be subsequently attached to tubing and to rest upon the upper end of the packer or an extension thereof, and close the same, substantially as described.

6. The combination with a well packer having a coupling sleeve at its upper end, 35 of a tubing extending continuously down through the packer, a connecting device carried by the tubing and capable of engaging and disengaging the coupling sleeve by a rotary movement of the tubing and device, 40 and another device having means for its attachment to the tubing, and having a gasket arranged to seat upon and close the upper end of the coupling sleeve around the tubing, substantially as described.

45 In testimony whereof, I have hereunto set my hand.

DAVID W. BLACK.
